(57) **CLAIM**

The ornamental design for a mint container, as shown and described.

DESCRIPTION

FIG. 1 is a perspective view of a first embodiment mint container, in accordance with the present invention;

FIG. 2 is a front elevational view of the mint container shown in FIG. 1;

FIG. 3 is a rear elevational view of the mint container shown in FIG. 1;

FIG. 4 is a top plan view of the mint container shown in FIG. 1;

FIG. 5 is a bottom plan view of the mint container shown in FIG. 1;

FIG. 6 is a right side elevational view of the mint container shown in FIG. 1;

FIG. 7 is a left side elevational view of the mint container shown in FIG. 1; and,

FIG. 8 is a perspective view of a second embodiment of the mint container of FIGS. 1–7, it being understood that all surfaces are the same as those of the first embodiment, the only difference being that the container is opaque and has no horizontal line on the side surfaces.

The broken lines in the drawings represent environmental structure and form no part of the claimed design.
